UNITED STATES PATENT OFFICE.

PAUL GERLI, OF NEW YORK, N. Y.

HYDROPLANE-STATION.

1,392,931.

Specification of Letters Patent. Patented Oct. 11, 1921.

Application filed January 21, 1919. Serial No. 272,230.

To all whom it may concern:

Be it known that I, PAUL GERLI, a citizen of the United States, residing at New York city, borough of Manhattan, county and State of New York, have invented certain new and useful Improvements in Hydroplane-Stations, of which the following is a full, clear, and exact description.

The primary object of the invention upon which the present application for Letters Patent is based is to provide at desired points in the high seas, stations for hydroplanes, which will permit of stop-overs for such machines when sent on long journeys over seas, will afford bases from which they may operate at great distances from shore, and will provide means for the storage of fuel, supplies and ammunition for such machines when on long journeys, and thus avoid the necessity of loading them with such freight in amounts which would tend to impair their practical value and efficiency.

For accomplishing these objects I have devised and designed floating and controllable stations which may be towed or impelled to such points as may be necessary or desirable, and maintained thereat by anchors or by suitable propelling devices, operating against the wind, and which are constructed to afford harbors or havens in which the traveling hydroplanes may alight from the air, or into which they may be guided or propelled from any point on the surface of the sea in the vicinity.

I believe that practical considerations impose for such stations certain structural features, and these I have developed to produce a station of the following general character: A sufficiently strong and watertight hull is constructed with one end approximately pointed like the bow of a ship, and the other end wider and open except below the water line in order to permit planes to float over the same. The interior space within the structure, whether formed with a complete or partial or no bottom, is below the water level to form a lagoon or harbor in which the planes alight or rest, and the side portions are built up to a sufficient height to afford a protective shelter around this lagoon.

This structure is equipped with propellers or revolving blades placed so that when operated by proper engines they may keep the pointed or bow end into the wind, or even serve as a means for propelling the craft,

and the superstructure of the side portions is provided with houses or store-rooms, wireless outfit, anti-aircraft, and other guns, and such other appurtenances as the nature of the case may require.

Specifically, the plan of construction may be very greatly varied, and the invention is not limited in this regard. In the accompanying drawings, however, I have illustrated the form and arrangement which I believe to be best adapted for practical use.

In these drawings:

Figure 1 is a top plan view of one of the improved stations.

Fig. 2 is a view of the same in side elevation, and

Fig. 3 is a cross section of the same.

In the construction shown there is a hull 1, preferably built up of water-tight compartments and substantially cigar-shaped, but with the central rear portion 2 covered over and on a level below that of the water in which the structure floats and open at the rear end. The sides 3 of the hull are built up to the desired height above the water level and may be, and preferably are, entirely covered or inclosed. At or near the pointed end 4 are rotary blades 5 driven by suitable engines 6 within the hull and the entire top may be provided with a guard rail 7.

Upon the covered portion or deck and preferably aft may be built houses 8, on one or both sides, for stores, to accommodate the crew of the craft or of arriving planes, and to contain the wireless outfit 9, ammunition and the like. These houses are reached by stairways or ladders 10 leading up from the lagoon as shown in Figs. 1 and 3.

The superstructure may also carry guns 11, search-lights 12, and the usual appurtenances of any sea-going craft. The structure may be provided with anchors or with steady beams or bars 13, and in case of need, with protective torpedo nets 14, suspended around its hull.

The craft should be made of very substantial dimensions so that its purpose and functions will not be materially interfered with nor its stability impaired by the heaviest storms or the largest waves. I design to place these stations at distances of 400 or 500 miles apart at sea, where, if they may not be anchored they may keep approximately in the same latitude and longitude by means of their propellers. Hydroplanes on

- long journeys may thus find refuge after flights of no extraordinary distances, and places where their crews may rest and where their fuel and stores may be replenished.
- 5 If the water is smooth the plane may alight near the structure, or if the sea is rough or the wind high, they may come up in the wind and alight in the lagoon or inclosed space within the structure. When once 10 within the lagoon, the crews may reach the superstructure in small boats and by ascending the stairways or ladders.

This invention, aside from its value in case of war, goes far toward solving the 15 problem of aerial transportation of mails, freight and passengers across the sea, for these stations may readily be built of sufficient strength and size to withstand the severities of storms and wind and may easily 20 be maintained in approximately fixed positions in all kinds of weather.

The lagoon within the structure has its opening restricted as shown, which restricted opening provides smoother water within the 25 lagoon than would otherwise be the case. The extended rear submerged end 2 also makes the water much smoother and the submerged floor 15 preferably extends entirely under the lagoon, thereby preventing 30 the force of the waves from coming up from below and unduly disturbing the water in

the lagoon. The lower part of the hull and superstructure are integral, thereby affording a stronger construction than a raft like structure with pontoon buoy like supporting 35 means.

At the end of the lagoon there is provided a platform 16 which is above the water line. The planes may be drawn out on this platform for repairs.

40 What I claim as my invention is:—

1. A hydroplane station composed of a hull, a superstructure built around three sides of a central open portion below the water-line forming a lagoon with restricted 45 inlet, portions of said hull forming a submerged floor for said lagoon, said superstructure comprising houses for stores and having a deck with stairways leading down to the lagoon.

50 2. A hydroplane station composed of a hull and superstructure adapted to form an inclosed lagoon in which hydroplanes may alight or into which they may float from the surrounding water, said hull having a 55 deck portion adjacent the water-line of the lagoon upon which hydroplanes may be drawn up for repairs.

In testimony whereof I hereunto affix my signature.

PAUL GERLI.
